UNITED STATES PATENT OFFICE.

CHARLES W. JUDD, OF LOWELL, MASSACHUSETTS, ASSIGNOR TO GORDON C. BIXBY, OF LOWELL, MASSACHUSETTS.

LEVER-PRESS.

1,270,620.

Specification of Letters Patent. Patented June 25, 1918.

Application filed July 19, 1917. Serial No. 181,467.

To all whom it may concern:

Be it known that I, CHARLES W. JUDD, a citizen of the United States, residing at Lowell, in the county of Middlesex and 5 Commonwealth of Massachusetts, have invented a certain new and useful Improvement in Lever-Presses, of which the following is a specification.

This invention relates to lever presses or 10 presses in which pressure is applied to the plunger or follower by a lever.

The object of this invention is to make a serviceable and durable press at a slight cost, to provide means for preventing the 15 expansion of the contents of the press between the successive applications of pressure and to keep the contents compressed while wiring or tying.

In the accompanying drawing Figure 1 is 20 a front elevation of a lever press embodying my invention, the door being open; Fig. 2, a left side elevation of the same, a part of the side of the box or press body being broken away; Fig. 3, a plan of the same, a 25 part of the follower being broken away; the press in each figure being represented as containing material to be pressed.

The box or frame A may be of any usual shape in cross section but is represented as 30 rectangular and as provided with a door a, through which a pressed bale or package may be removed. Within the box A is arranged a plunger or follower B, provided with a stem or plunger-rod b. The parts 35 above specified may all be of usual construction and operation except as hereinafter stated.

The upper portion of the vertical stem b of the plunger B is provided on both sides 40 with projections b¹, consisting preferably of pins driven through said stem and extending from the opposite sides thereof equally at right angles therewith to a distance as great as the lateral thickness of one of the levers 45 C C¹. The two levers C C¹ are represented as alike, being levers of the second order pivoted on opposite sides of a vertical fulcrum-post D by a bolt c which passes through said levers and post, said post being 50 rigidly secured to the back of the box A directly behind the stem b of the plunger. The bearing of the levers on the bolt c is loose enough to allow each lever to swing 55 away from the stem b far enough to pass the free ends of the projections b¹, so that each

lever may be moved from one of the corresponding projections to another as the plunger descends, in order that the swing of said levers may be worked through short arcs and the pressure upon the plunger may 60 vary as little as possible from the perpendicular. Each lever is provided on the under side with an arc-shaped notch c¹ to keep the stem of the plunger from moving too far from a vertical position and thus to 65 keep the plunger in an approximately horizontal position or parallel with the bottom of the box.

The levers may be used simultaneously or alternately. When the material to be compressed is first placed in the box and is in a loose condition, offering little resistance, both levers may be used at the same time for a few strokes but when the resistance 70 becomes greater it will be more advantageous to hold one of the levers down to prevent the material from rising while the other lever is swung away from the stem to clear the projections on the corresponding side of the stem and raised into engagement with 75 another higher projection for another downward movement of the plunger, thus operating the levers alternately on opposite sides of the stem. A vertical locking post E is secured to the front of the box A above the 80 door a in alignment with the fulcrum post D and stem b between the levers C C¹ and is perforated laterally to receive a pin F which may be passed through said post E above both levers to prevent the compressed 85 contents of the press or bale from expanding 90 while being wired or tied.

I claim as my invention:

1. In a lever press, the combination of a box, a plunger having a stem and a pair of 95 levers fulcrumed on said box and arranged on opposite sides of said stem, said stem being adapted to be engaged by said levers independently of each other.

2. In a lever press, the combination of a 100 box, a plunger having a stem, a pair of levers, each fulcrumed on said box, and arranged on opposite sides of said stem, and a series of projections on opposite sides of 105 said stem, the projections of each series adapted to be engaged singly by the lever at the same side of said stem.

3. In a lever press, the combination of a 110 box, a plunger having a stem, a pair of levers fulcrumed on said box and arranged

on opposite sides of said stem, said stem being adapted to be engaged by said levers independently of each other, a post secured to said box in alinement with said fulcrum and 5 stem and provided with holes and a pin adapted to be passed through a hole above said lever post to prevent the rising of said plunger.

4. In a lever press, the combination of a 10 box, a plunger having a stem, a pair of levers, each fulcrumed on said box, and arranged on opposite sides of said stem, and

a series of projections on opposite sides of said stem, the projections of each series adapted to be engaged singly by the lever 15 at the same side of said stem, the under sides of said levers having grooves to receive said projections.

In witness whereof I have signed this specification in the presence of two witnesses. 20

CHARLES W. JUDD.
